UNITED STATES PATENT OFFICE.

JAMES S. LESTER, OF ATLANTA, GEORGIA.

COVERING FOR BRICK-HACKS.

SPECIFICATION forming part of Letters Patent No. 314,457, dated March 24, 1885.

Application filed May 21, 1884. (No model.)

To all whom it may concern:

- Be it known that I, JAMES S. LESTER, a citizen of the United States, residing at Atlanta, in the county of Fulton and State of Georgia, have invented certain new and useful Improvements in Coverings for Brick-Hacks, of which the following is a specification, reference being had therein to the accompanying drawings.
- 10 My invention relates to coverings for brick-hacks, and is designed to replace the ordinary drying-sheds in brick-yards; to provide a removable covering for protecting the drying bricks from rain; to provide a covering that may be easily and quickly placed in position and taken off; to provide a covering that will thoroughly protect the lower courses of the brick from spattering, and will conduct the water during a rain-storm off at one end, 15 and also provide a covering that, during drying weather, may be packed in a small compass in any convenient portion of the said brick-yard. Furthermore, the device is more satisfactory in operation, simpler and far less cumbersome in construction, and cheaper than the usual "shed."
- 20 In describing the construction and operation of the device, reference will be made to the annexed drawings, in which—
- 25 Figure 1 represents a cross-section through a hack of bricks covered by the protecting covering, and Fig. 2 a longitudinal section through the same.
- 30 A represents a pile of green bricks, drying preparatory to "kilning," and protected from rain by the improved covering. This covering consists of a frame-work formed of two longitudinal strips, B, secured at the ends of the cross-pieces C, and also a central longitudinal strip, D. Secured to the surface of each of the strips is a covering of cloth, metal, or other material, E, projecting over the edges of the frame and falling downward to such a distance as to reach the ground, as shown at 35 F. Between the strips of the frame the material "sags" somewhat and forms two long gutters, G, for conducting the water through the length of the hack or hacks. Where the hack is longer than the covering, or where a 40 series of them are placed in line, the projecting end H of the covering overlaps the end of the covering on the next hack, and so on, thus properly conducting the water. As will readily be seen, the sides are thoroughly protected from spattering.
- 45 The falling sides being made of flexible material they may be folded in packing, and thus take but little room.
- 50 It will also be seen that the construction is effective, simple, and cheap, and the device 60 operated with the greatest ease.
- 55 The right to vary the construction consistent with the spirit of the invention is reserved.
- 60 Having described the device, what I claim 65 is—
1. A removable covering for brick-hacks, consisting of a frame supporting a flexible covering which is formed into one or more longitudinal gutters on the said frame, sub- 70 stantially as and for the purpose specified.
2. A removable protector or covering for brick-hacks, consisting of a frame supporting a flexible covering which projects longitudinally beyond the said frame on one or both 75 ends, so as to rest on the next succeeding cover, thus forming a continuous protector of two or more sections, substantially as and for the purpose specified.
3. A removable protector or covering for 80 brick-hacks, consisting of a frame supporting a flexible covering which falls on each side of the hack, is formed into longitudinal gutters in the said frame, and projects longitudinally beyond one or both ends of the 85 frame, substantially as and for the purpose specified.
4. A removable protector for brick-hacks, consisting of a flexible covering falling on each side the said hack, formed into one or more 90 gutters extending longitudinally on top the hack and also beyond one or both ends thereof, and a supporting-frame formed of two or more longitudinal strips between which is a central strip of less vertical diameter, the said 95 strips being connected by suitable cross-pieces, all arranged substantially as and for the purpose specified.
5. A removable protector for brick-hacks, consisting of a flexible covering and a frame 100 supporting the same, and formed of two longitudinal strips, and a central strip of less vertical diameter, and suitable connecting cross-pieces, all arranged substantially as and for the purpose specified.
- 105 In testimony whereof I affix my signature in presence of two witnesses.

Witnesses: JAMES S. LESTER.
